UNITED STATES PATENT OFFICE.

FRANK B. BIGELOW, OF DETROIT, MICHIGAN.

FURNACE-ARCH CONSTRUCTION.

Application filed July 25, 1925. Serial No. 46,017.

My invention relates to improvements in the means for supporting refractory bricks in furnace roofs or arches, and in similar relations, and pertains more particularly to a construction of this character for sustaining or supporting the bricks at the nose or end of the roof or arch in such manner that they will not be subjected to strains due to the weight of the parts, and those due to the varying temperatures, but will be independently supported and will not impose their weights upon one another.

Stated somewhat differently, in the new construction incorporating the preferred embodiment of the invention, the sector-shaped holders or supporting members for the bricks or refractories are so designed and arranged, and the refractory shapes are so proportioned, that when the several parts are assembled the weight will be carried entirely by the metal construction, and spaces allowed between the bricks or refractories to avoid their carrying anything but their own weight, and as the construction is heated and expansion takes place, the expansion pressure will be cared for by the iron-work, the bricks being entirely relieved in this regard.

More specifically, in the preferred embodiment of the invention as exemplified in a fan-shaped construction, I employ a main support and detachably position thereon a plurality of pocket or socket members designed to carry the bricks out of contact with one another, the strains due to the weight of the parts and those caused by the varying degrees of heat being imposed solely on the supporting elements, and not on the refractories themselves.

To enable those acquainted with this art to understand the new construction and its various structural and functional advantages, in the accompanying drawing, forming a part of this specification, I have illustrated a desirable and preferred embodiment of the invention, and for simplicity I have employed like reference characters for the same parts throughout the several views.

In this drawing,—

Fig. 1 is a fragmentary, vertical section through the end portion of a furnace-roof

construction, and illustrates the new invention incorporated therein;

Fig. 2 is a vertical section of the structure on the bent line 2—2 of Fig. 1, the parts being viewed in the direction indicated by the arrows;

Fig. 3 is a perspective view of one of the flaring or tapered bricks or refractories;

Fig. 4 is an end view of one of the demountable brick-supporting pocket members; and

Fig. 5 is a face view or elevation of the same.

Referring to these several views of the drawing, it will be seen that a portion only of the main brick arch 11 of the flat type is illustrated, the bricks thereof being supported or suspended from above by pipes 12, 12, carried on suitable beams 13, hangers 14, 14, depending from such pipes, and shoes 15 fitted in slots or grooves of the bricks which unitedly form the arch or roof for the furnace.

Above the rear or inner end of this arch, 75 there is a pair of spaced, cross I-beams 16 and 17, and mounted on these I provide a series or row of spaced, quadrant members 18, 18, bolted at 19 to the web of the supporting beam 16, and each having a hook-shaped part 21 engaging the lower flange of the companion beam 17, and another section 22 bearing on the bottom flange of the beam 16.

The exact and precise manner of mounting such supporting members 18 is of minor importance, and any approved or appropriate method, such as will readily occur to those skilled in this art, may be employed.

The quadrant sector 23 of each such element 18 comprises a web having a curved edge, a main aperture 24 through such web, and small holes therethrough, referred to hereinafter.

Each such web or quadrant portion has 95 four pairs of horizontal lugs or ears 25, 25, outstanding in register from its opposite sides.

For holding the several bricks in fan or arc shaped formation or relation on such common support 18, I use a plurality of metal, sector, pocket or socket members 26

and 27, of two slightly different types, although in their general characteristics they are much alike.

- Each of the socket members 26, 27, of each 5 vertically-disposed set or group has a flaring recess 28 with opposite walls 29 and 31, each supplied with a longitudinal rib 32 on its inner surface designed and intended to fit in oppositely-disposed grooves 33, 33 in opposite, diverging faces of two tapered bricks 34 intended to be received in the socket or pocket, the ribs supporting the bricks and preventing them from falling out, as will be readily understood.
- 15 As is indicated in Figs. 4 and 5, the ends of such pockets or recesses are open, whereby the bricks or refractories may be easily slid into place before the member 26 or 27, as the case may be, is mounted on the corresponding, supporting, quadrant element.

One, two or more bricks, as desired or preferred, may be carried in each such pocket, but in the present case two have been shown as so used.

- 25 Each such brick-supporting, socket-member 26 has a pair of apertured, spaced arms 35, 35, arranged to straddle the web 23, and they are held and supported thereon by a bolt 36 extending through the aligned holes 37 of such arms, and through a registering aperture in the intervening quadrant member.

Thus the three lower rows of such brick-carrying members, which bear against one 35 another, as shown, are supported by such bolts, and their turning on these sustaining elements is restricted or limited by the engagement of the edges of their arms 35 with the corresponding, outwardly-projecting 40 lugs or abutments 25 referred to above.

By removing the proper bolt, any one of such brick-sustaining members 26 may be easily and readily taken out to replace a burned or injured brick by a new one, and 45 replaced with equal facility, it being assumed, of course, that the bolts are accessible for such removal.

The brick-carriers of the top or upper row are like those of the lower rows except that 50 the straddling ears or arms are somewhat longer and of slight hook-shape, whereby they may not only bear against, but also hook around, the corresponding lugs 25, as is clearly depicted in Fig. 1.

55 As in the previous instance, these refractory-supporting socket-members rest on or contact with the lower ones, so that all of them may be considered as bearing on one another in series, each resting on the one below, at least in part, and sustaining those above, at least partially, the group forming a fan-shaped or arcuate ensemble.

To remove an upper pocket-member and its brick or bricks, they are rocked upward- 65 ly somewhat until the ears or arms 35 are

freed or unhooked from their associated or cooperating lugs 25, whereupon they may be conveniently withdrawn or demounted, the damaged brick or bricks replaced by one or more others, and the whole readily re-mounted in position.

If preferred, the second row of bricks from the top may be mounted as are those of the upper row, or if desired, all of the rows of bricks may be mounted in either manner, 75 but the present preferred method is that depicted in the drawing and described above.

Substantial modifications and changes may be made in this embodiment of the invention and still incorporate the essential 80 features of the invention as defined by the following claims and without sacrificing any of the material benefits arising from employing the invention.

I claim:

1. In a furnace-roof construction, the combination of a support having an outstanding lug, a first pocket-member adapted to accommodate a brick in it and constructed to hook around said lug, and a second underlying pocket-member adapted to accommodate a brick, said first pocket-member maintaining such interlocking engagement with said lug by bearing by gravity on such underlying pocket-member.

2. In a furnace-roof construction, the combination of a support having an outstanding lug, a pocket member mounted on said support and adapted to hold a brick, a second pocket member designed to hold a brick bearing on said first pocket member and against said lug.

3. In a furnace-roof construction, the combination of a support, and a plurality of pocket members mounted on said support and resting on one another in series, each of said pocket members being constructed to accommodate one or more bricks, the latter thus supported being out of bearing contact with one another.

4. In a furnace-roof construction, the combination of a support, and a plurality of converging pocket members mounted on said support and resting on one another in series, each of said pocket members constructed to accommodate one or more bricks, the latter thus supported being out of bearing contact with one another.

5. In a furnace-roof construction, the combination of a support having oppositely-extending outstanding lugs, and a pocket member adapted to accommodate a brick having spaced arms to straddle said support and engage the corresponding lugs.

6. In a furnace-roof construction, the combination of a support having a series of oppositely-extended outstanding lugs, and a series of pocket members adapted to accommodate bricks, said members bearing on one another and each having spaced arms strad-

dling said support and engaging its cor- responding pair of lugs.

7. In a furnace-roof construction, the combination of an apertured support, a pocket member having an apertured arm and adapted to internally accommodate a brick, said support having a lug against

which said arm is designed to bear, and a bolt extended through the apertures of said arm and support.

In witness whereof I have hereunto set my hand and seal.

10

FRANK B. BIGELOW. [L. s.]
